(57) **CLAIM**

The ornamental design for sink for kitchen as shown and described.

DESCRIPTION

FIG. 1 is a perspective view of the sink for kitchen of the present invention;

FIG. 2 is a top view thereof;

FIG. 3 is a bottom view thereof;

FIG. 4 is a front view thereof;

FIG. 5 is a rear view thereof;

FIG. 6 is a left view thereof;

FIG. 7 is a right view thereof;

FIG. 8 is a cross-sectional view thereof taken along line A-A of FIG. 2;

FIG. 9 is a cross-sectional view thereof taken along line B-B of FIG. 4;

FIG. 10 is a cross-sectional view thereof taken along line C-C of FIG. 4; and,

FIG. 11 is a cross-sectional view thereof taken along line D-D of FIG. 4.

The broken lines and the portions between the broken lines represent unclaimed portions of the sink for kitchen and form no part of the claimed design.

1 Claim, 5 Drawing Sheets
